SAILBOAT WITH RETRACTABLE HATCH COVER

Charles William Lapworth, 505 30th St.,
Newport Beach, Calif. 92660

Filed Dec. 6, 1965, Ser. No. 70

Term of patent 14 years

FIGURE 5 is a broken perspective view from the rear and top of the cabin of said sailboat showing said hatch cover in a retracted position; and

The dominant features of my design reside in the portions shown in full lines.

I claim:

The ornamental design for a sailboat with retractable hatch cover, substantially as shown and described.
